UNITED STATES PATENT OFFICE.

KENNEDY DOUGAN, OF MINNEAPOLIS, MINNESOTA; MINNEAPOLIS TRUST COMPANY, OF MINNEAPOLIS, MINNESOTA, EXECUTOR OF THE SAID KENNEDY DOUGAN, DECEASED.

PENCIL SHARPENER.

Application filed January 27, 1923. Serial No. 615,398.

To all whom it may concern:

Be it known that I, KENNEDY DOUGAN, a citizen of the United States, and a resident of Minneapolis, in the county of Hennepin and State of Minnesota, have invented new and useful Improvements in a Pencil Sharpener, of which the following is a specification.

One object of my invention is to provide a sharpener for lead pencils and the like that can be easily operated with one hand.

Another object is to provide a pencil sharpener that will sharpen a pencil when the device is given a reciprocal motion.

Another object is to provide in a pencil sharpener having a cutting edge means for causing the rotation of the cutting edge through the reciprocating motion of the device.

Another object is to provide means for transforming the reciprocating to a rotating motion with the minimum amount of friction.

Another object is to provide an improved form of grip for the pencil.

With these and incidental objects in view, the invention consists of certain novel features of construction and combinations of parts, the essential elements of which are hereinafter described with reference to the drawing which accompanies and forms a part of this specification.

In the drawing, Figure 1 is a side elevation of my device shown attached to the under part of a table.

Figure 2 is a fragmentary sectional view taken on a longitudinal axis.

Figure 3 is a section taken on the line 3—3, Figure 2.

Figure 4 is a top view of the device, Figure 5 is a section taken on the line 5—5, Figure 4.

As shown, the pencil sharpener consists of a body 1 in which is mounted a rotatable head 2 carrying a cutting knife 3. Extending from this head 2 is a spirally twisted metal strap 4 which forms a double threaded screw.

The bracket 5 has mounted on the depending feet 6 grooved anti-friction rollers 7 set at an angle to readily receive the edges 8 of the screw thread.

A pencil may be inserted into the head

as shown at 9 and the body is slotted at 10 to allow it to grip the pencil.

The pencil positioned in the head is gripped by the hand with the thumb or finger or both holding the external part of the body 1 and also the pan 11, then when the hand is moved back and forth horizontally the screw will be rapidly turned by the reaction of the rollers 7, thereby causing the head 2 with the cutting edge 3 to rotate in the body 1, thus sharpening the pencil in the customary manner.

The pan 11 snaps over the body encircling the barrel thereof as plainly shown at 12 in Figures 4 and 5 and receives the turnings from the pencil and may be readily detached and emptied when it becomes full.

The ordinary type of pencil sharpener requires the use of two hands so the advantage to a draftsman, or anyone steadily working at a bench or table in being able to sharpen a pencil with one hand only is easily recognized by anyone who has ever engaged in this line of work.

While I have described my invention and illustrated it in one particular design, I do not wish it to be understood that I limit myself to this construction as it is evident the application of the invention may be varied in many ways within the scope of the following claims:

1. In a pencil sharpener, the combination of a body adapted to receive and grip the pencil therein with a cutter head rotatably mounted in said body, a mounting frame for the device and means connecting said head and said frame for translating a reciprocating motion applied to said body into a rotative movement of said head.

2. In a pencil sharpener, the combination of a frame with grooved pulleys mounted on said frame, a screw co-acting with said pulleys whereby a reciprocating movement of said screw rotates said screw and a cutting edge, rotatable by said screw.

3. In a pencil sharpener, the combination with a body, of a cutter head rotatably mounted in said body, a cutting edge carried by said head, a screw extending from said cutter head, a mounting frame, and anti-friction grooved rollers co-acting in nut-like fashion with said screw.

KENNEDY DOUGAN.
